LOUVER ASSEMBLY FOR WINDOW OPENING

Paul J. Howard, Los Angeles, Calif.

Application May 13, 1955, Serial No. 508,187

6 Claims. (Cl. 230—259)

This invention relates to window construction and is particularly directed to a novel form of a device utilizing louvers which extend radially from a central hub.

It is an object of this invention to provide light or air control for a window using louvers which tilt about radial axes. In closed position, the edges of the louvers overlap, and in open position, the louvers present a minimum of obstruction for entrance of light and air.

Another object of this invention is to provide novel means for simultaneously controlling movement of all of the louvers.

Another object is to provide a louver assembly of this type which may be turned in the manner of a fan to draw air into a room or to expel air therefrom.

Other related and more detailed objects and advantages will appear hereinafter.

In the drawings:

Figure 1 is an elevation showing a preferred embodiment of my invention.

Figure 2 is a sectional elevation taken substantially on the lines 2—2 as shown in Figure 1.

Figure 3 is a sectional view on an enlarged scale taken substantially on the lines 3—3 as shown in Figure 2.

Figure 4 is a sectional view taken substantially on the lines 4—4 as shown in Figure 2.

Figure 5 is an elevation on an enlarged scale drawing the louvers in closed position.

Referring to the drawings:

The stationary window frame generally designated 10 is provided with a series of rollers 11 which engage the outer periphery or rim 12 of a louver assembly generally designated 13. Louvers 14 are mounted in a series about a central hub 15. Each louver 14 is provided with an outer pin 16 which is pivotally received within a bearing 17 mounted on the rim 12. Each louver is also provided with a pin 18 which is pivotally received within a radial bore 19 provided in the hub 15. A ball bearing element 20 may be provided to reduce friction. The pins 16 and 18 are mounted in radial alignment and may be fixed to the individual louver by any convenient means, such as for example, fasteners 21.

The hub 15 is fixed on a hollow shaft 22 by means of set screw 23, the hub and shaft functioning as a single hub member. An annular plate 24 is mounted to turn on the hollow shaft 22 and carries a ring gear 25. A pinion gear 26 is fixed to each of the radial pins 18 and meshes with the ring gear 25. A U-shaped control handle 27 is fixed to the plate 24 and provides a means for turning the plate 24 with respect to the hollow shaft 22. From this description it will be understood that turning movement of the plate 24 and ring gear 25 relative to the hollow shaft 22 and hub 15 serves to turn the pins 18 and thereby change the angle of inclination of the louvers 14. A clamping nut 28 is threaded on the end of the hollow shaft 22 and serves to fix the louvers 14 at any selected annular position.

The louvers can be turned to the fully open position shown in Figure 1 to one of two fully closed positions.

2

One fully closed position is indicated in Figure 5, and the other fully closed position is similar, except that the louvers overlap clockwise instead of counterclockwise. In the open position, the plane of each louver contains the axis of the hollow shaft 22 and the louvers thus present a minimum of obstruction for light and air. In either closed position, the edge of each louver 14 overlaps the edge of an adjacent louver with the result that the window is effectively closed against passage of either light or air. It will be observed that each louver is generally triangular in shape. The outer edge being curved to conform to the inner diameter of the rim 12 and the inner end being squared off instead of pointed.

The cam 29 which is fixed to the shaft by means of the set screw 30 is also fixed to four radiating spokes 31 by means of fasteners 32. These spokes 31 are equally spaced and are joined to the rim 12 adjacent one of its edges.

Means are provided for turning the entire louver assembly 13 in the manner of a fan. As shown in the drawings, this means includes a reversible variable speed electric motor 33 mounted on brackets 34 and stationary cross bars 35. The projecting drive shaft 36 of the motor extends into the bore 37 of the hollow shaft 22 and is connected to drive the shaft 22 by means of a key 38. When the motor 33 is energized the shaft 22, hub 15, louvers 14 and rim 12, rotate about the axis of the shaft. The rollers 11 maintain the assembly 13 in position while it turns. The angularity of the individual louvers 14 determines whether air is drawn into or out of the window opening as well as the amount of air flow in cubic feet per minute.

Instead of placing the motor 33 in axial alignment with the shaft 22, the motor may be mounted in a stationary position outside the periphery of the rim 12 and arranged to drive the shaft by means of a belt or chain, or through a shaft drive and a pair of bevel gears. Or the motor 33a may be located as shown by the phantom lines in Figure 1 and connected to turn a drive roller 39 in friction contact with the outer surface of the rim 12.

Having fully described my invention, it is to be understood that I do not wish to be limited to the details herein set forth, but my invention is of the full scope of the appended claims.

45 I claim:

1. In a window construction, the combination of: a frame, a rim mounted within the frame, a hub member mounted centrally within the rim, a plurality of louvers extending radially between the hub member and the rim, means at the outer end of each louver for pivotally supporting it on the rim, means at the inner end of each louver for pivotally supporting it on the hub member, the louvers being shaped so that in closed position the edge of each louver overlaps that of an adjacent louver, a pinion gear fixed relative to each louver near the inner end thereof, a ring gear mounted on the hub member and meshing with each of said pinion gears, means whereby the ring gear may be turned relative to the hub member to move all of the louvers simultaneously about their respective pivot means, and means on the hub member for locking the ring gear in selected position.

2. In a window construction, the combination of: a frame, a rim mounted within the frame, a hub member mounted centrally within the rim, a plurality of louvers extending radially between the hub member and the rim, means at the outer end of each louver for pivotally supporting it on the rim, means at the inner end of each louver for pivotally supporting it on the hub member, the louvers being shaped so that in closed position the edge of each louver overlaps that of an adjacent louver, gear means for moving all of the louvers simultaneously

about their respective pivot means, said means including a ring gear mounted to turn on the hub member meshing with a series of pinion gears each fixed to one of the louvers, and means for locking the gear means in selected position, said means including a clamping nut threadedly mounted on the hub member and adapted to frictionally secure the ring gear relative to the hub member.

3. In a window construction, the combination of: a plurality of louvers radiating from a central hub member, and adapted to be mounted in a window opening, movable means on the hub member for simultaneously turning all of the louvers about their respective axes through substantially one-half revolution to either one of two closed positions, the louvers being shaped so that in either closed position the edge of each louver overlaps that of an adjacent louver, means on the hub member locking the louvers in adjusted position and means for rotating all of the louvers as a unit within the window opening.

4. In a window construction, the combination of: a frame, a rim mounted to turn within the frame, rollers on the frame engaging the rim, a hub member mounted centrally within the rim, a plurality of louvers extending radially between the hub member and the rim, means at the outer end of each louver for pivotally supporting it on the rim, means at the inner end of each louver for pivotally supporting it on the hub member, whereby each louver may turn through substantially one-half revolution to either one of two closed positions, the louvers being shaped so that in either closed position the edge of each louver overlaps that of an adjacent louver, gear means whereby all of the louvers may be moved simultaneously about their respective pivot means, means on the hub member for locking the gear means in selected positions, and means for rotating all of the louvers as a unit.

5. In a window construction, the combination of: a frame, a rim mounted to turn within the frame, rollers on the frame engaging the rim, a hub member mounted centrally within the rim, a plurality of louvers extending radially between the hub member and the rim, means

5 at the outer end of each louver for pivotally supporting it on the rim, means at the inner end of each louver for pivotally supporting it on the hub member, the louvers being shaped so that in closed position the edge of each louver overlaps that of an adjacent louver, gear means whereby all of the louvers may be moved simultaneously about their respective pivot means, means on the hub member for locking the gear means in selected position, arms connecting the rim and the hub member, and power means for turning the hub member and thereby to rotate the hub member, rim, and louvers as a unit.

10 6. In a window construction, the combination of: a frame, a rim mounted to turn within the frame, rollers on the frame engaging the rim, a hub member mounted centrally within the rim, a plurality of louvers extending radially between the hub member and the rim, means at the outer end of each louver for pivotally supporting it on the rim, means at the inner end of each louver for pivotally supporting it on the hub member, the louvers being shaped so that in closed position the edge of each louver overlaps that of an adjacent louver, means whereby all of the louvers may be moved simultaneously about their respective pivot means, means on the hub member for locking the louvers in selected position, and means for turning the rim to rotate all of the louvers as a unit.
